UNITED STATES PATENT OFFICE

2,498,904

APPARATUS FOR EXPANDING SLAG

Dee G. Wheeler, Chicago, Ill., assignor to The Celotex Corporation, Chicago, Ill., a corporation of Delaware

Application April 13, 1948, Serial No. 20,631

5 Claims. (Cl. 49—14)

1

This invention relates to a new and improved apparatus for producing a slag aggregate, and in particular the so-called expanded slag aggregate. Such expanded slag aggregate is used in lieu of crushed rock, gravel, and the like, in the preparation of concrete to provide light weight concrete, both monolithic and in shape form, that is, as blocks or various other formed products.

The objects of this invention are to provide a new and improved form of apparatus for use in expanding slag for use as light weight slag aggregate in particular, to provide such an apparatus which is simple in operation, is rugged, and in which there are no moving parts involved in the procedure of expanding or causing puffing of the slag in order that the slag may be expanded to a light weight.

In the drawings, wherein like numerals are applied to like parts in the various figures,

Figure 1 comprises a section taken on line 1—1 of Figure 2;

Figure 2 is a section taken on line 2—2 of Figure 1; and

Figure 3 is a section taken on line 3—3 of Figure 1.

The use of the apparatus disclosed herein is not limited to its use in expanding slag from any particular source, but in general the most convenient slag source is the steel blast furnace, and for the purposes hereof the description and use of the apparatus will be discussed from the viewpoint of apparatus for and production of expanded slag from blast furnace slag. Other suitable slags, of course, may be used, as, for example, slag from a foundry cupola or slag from a zinc smelter, or the like, or, in some cases, suitable rock and/or fluxes may be melted down and then expanded by the use of the apparatus hereof for providing expanded aggregate, that is, one from what might be termed a "synthetic" slag.

The apparatus must be rugged and capable, in particular, of standing up under high temperatures, since slag from a blast furnace is usually tapped off at a temperature of around 2400° F., and due to the conditions to which the apparatus is subjected, that is, because of the abrasive conditions which exist, with accompanying high temperatures, it is substantially imperative that the apparatus not include rotating parts requiring bearings or close fit of any nature.

The device hereof has no moving parts, and all parts thereof may readily be constructed of such materials and in such manner that to all

5 intents and purposes there is nothing to wear out due to the abrasive and high temperature conditions, and thus the upkeep and maintenance of the apparatus will be kept at a minimum.

There is provided, as part of the device, a slow moving conveyor which is provided at the bottom of the device for carrying away the slag after it is expanded, but this is a very slow moving device and it may readily be designed so as to be relatively unaffected by its conditions of operations, particularly so since this conveyor is not subjected to the extremely high temperature of the molten slag, but is merely subjected 10 to the lower temperature of the somewhat cooled slag after it has been expanded in the apparatus.

The apparatus comprises a suitable chamber 20 constructed of stone, brick, concrete, or the like, and is of a considerable diameter with the illustration, thereof considered to represent such construction of approximately 10 feet in diameter and of a height of about 14 feet. This chamber or, rather, the walls thereof are designated on the drawing by the numeral 10. It 25 is to be understood, of course, that, preferably, at least the inner facing of the walls of such construction are composed of suitable refractory material which will withstand subjection to high temperature, but as this is merely a matter of 30 selection well within the scope of the knowledge of those skilled in the art, there will be no specific discussion of the particular materials to be used in the erection of the walls 10 or the details of erection.

35 Preferably, and in order that there may be a greater latitude in the selection of the materials comprising wall 10 in its upper portion, there may be provided within, and as a lining, therefor, an annular cooling chamber designed at 11. The chamber, as will be apparent from the illustration, is preferably round at the top, that is, of circular outline, and its lower part is of a square outline. It is not critical as to the exact point at which the shape of the chamber should change from a round shape to a square shape, but for the purposes of construction it is convenient that just below the lower water-cooled grid 22 this change occur, so that the baffles, etc., below this point may be fitted to the rectangular shape rather than involve difficulty were the circular shape continued all the way down.

It is not deemed that any detailed description is required of the water-cooled annular lining 11, except to say that it is provided with suitable cooling water inlets, as at 13, and outlets,

as at 14, or vice versa, depending on whether it is preferred to circulate the cooling water, respectively, downwardly or upwardly through the cooling chamber. The purpose is merely that of protecting the interior of the wall 10 at its upper part from the high-temperature molten slag, and while a water-cooled chamber lining has been illustrated, it will be understood that there may be used in lieu thereof any suitable high-temperature refractory, and that the specific construction with respect to this feature is purely a matter of engineering design.

Located centrally of the structure, and slightly below the top thereof, there is provided what will be referred to as a target 12. Target 12 is shown as comprising a double-walled, water-cooled basin having suitable piping connected thereto to support the structure and to provide for supplying cooling water thereto. The inlet and outlet for the cooling water which circulates within the target 12 are also designated by the numerals 13 and 14, respectively, but here again, as will be well understood, the target may be formed of a suitable refractory material. For example, such high-temperature refractory as has lately been developed in connection with jet turbines, and the like, or, if desired, the upper surface of the double-walled target 12 may be provided with a protective coating of a high-temperature refractory material.

One or more of jets 20 may be air jets supplied with air at about 100 pounds per square inch. Such air jet will serve the same function as the water jets, but will be more effective in breaking up the slag stream into slag masses with less cooling at this stage of the process.

Also adjacent the top portion of the chamber, and extending through walls 10, there are illustrated spray nozzles which will be referred to as primary sprays and designated by the numeral 20. There are shown a plurality of primary spray heads, specifically 6 being shown, but it is to be understood that here again, depending on design, there might be used substantially any other number of sprays which, by way of example, may conveniently comprise as few as three, or even a lesser number, or may conveniently comprise up to 10 or 12, although the desired result could be obtained with an even greater number of such primary sprays. The purpose of these primary sprays 20 are to provide for a limited degree of cooling of the slag stream as it impinges on target 12 and, to a somewhat limited extent, to serve to break up the slag into separate masses. As shown in the drawings, and as is particularly evident in Figures 1 and 2, the primary jets 20 are directed downwardly, and more or less tangentially with respect to the upper surface of the target 12, and these should comprise jets rather than sprays since, as stated, it is the purpose of these jets 20 to impinge upon the slag stream just about as it contacts the target 12, and part of the function of these sprays, to a limited extent, at least, is to assist in breaking up the cooling slag mass.

Positioned below primary jet sprays 20 there are provided a plurality of secondary sprays 21 which are also shown as being six in number, although here again the number may be varied in accordance with the design. That is, with large sprays, high pressure, etc., there may be used a smaller number of sprays 21, or there may be a greater number of such spray heads of a smaller size and supplied with water at lower pressure. The function of these sprays 21 is to provide an actual spray rather than jets, and to spray the

slag masses as they fall over the edge of target 12, and these sprays 21 serve to further lower the surface temperature of the slag masses that are falling from target 12. Sprays 21 are also preferably arranged so as to spray, substantially, tangentially with respect to target 12, since, as is readily understood, there is nothing to be sprayed directly under the target.

Slightly lower down in the chamber, and shown as extending through the wall 10, there is provided grids designated by the numeral 22, which grids connect to suitable headers 23. Headers 23, at one end of each sets of grids, will comprise a cooling water inlet header, whereas, the header at the other end of the grid will comprise a cool-water outlet header. It is to be understood that these cooling water headers 23 will be suitably connected to a water supply and discharge so that cooling water may be circulated through the individual grid members 22. The grids 22, as is clearly shown, are spaced slightly, one below the other, and the individual grid members are respectively arranged at right angles, one to the other, so that a plan view thereof shows the checkerboard effect, clearly apparent in Figure 2 of the drawing. This grid will serve, to some extent, to slow up the fall of the slag masses which are formed above and fall from target 12, that is, some of such slag masses will hit the grids and be retarded so that overall the fall of the slag masses is slightly slowed down.

Below the grids 22 there are provided downwardly inclined baffles 31 provided with perforations 32 and having their outer ends more or less overlapping, as is clearly indicated in the drawings. The baffles 31 are for the purpose of receiving the slag masses after they have passed through the grids 22, and these baffles, being inclined downwardly, the slag masses falling thereon will tend to slide downwardly on the first baffle onto the second, and then from the second baffle to the next, should more of these baffles be provided. The function of these baffles 31 is to further slow up the falling of these slag masses. Since the inclination of the baffles is relatively small, that is, about 60°, the slag masses may tend to lay on the surfaces of the baffle, but as there is a large volume of slag falling, this material which subsequently falls will tend to force downwardly along the surfaces of the baffles such slag masses as may have been arrested on the baffles. Baffles 31 are provided with openings 32 through which any excess water may drain.

The slag masses will eventually be discharged from the lower inward end of the lowermost baffle 31, and below this baffle there is provided a low speed conveyor more or less similar to a chain grate. This conveyor, positioned near the bottom of the chamber, comprises a chain or link belt 27 which runs on sprockets 28, one of which may be driven by suitable power means. Preferably, between the runs of the conveyor 27, and in fact just under the upper run of conveyor 27, there is provided an additional downwardly inclined baffle, designated by the numeral 25, which baffle member is provided with drain openings 26. This baffle not only serves the function of supporting the upper end of the conveyor chain 27, but it also provides, due to the openings 26 therethrough, for the drainage of any free water away from the expanded slag masses which are deposited on chain 27. Of course, in lieu of chain conveyor 27, there may be provided other means for removing the expanded slag from the bottom of the chamber, and in fact, if desired, the ex-

expanded slag masses may be raked from the lower part of the chamber by hand, or any desired mechanical means may be provided for discharging the expanded slag from the lower part of the chamber.

In the operation of the apparatus hereof, molten slag from a blast furnace, or the like, is poured into the chamber at the top from any suitable ladle, or the like, and preferably the slag is poured therefrom as a stream impinging upon target 12. The slag stream, as it impinges upon target 12, is impacted by the cooling jets from spray heads 20 so as to be somewhat cooled down, and to some extent sub-divided into individual masses. Since the slag is preferably poured at quite high rate and continuously, while a pour is being made the material will rapidly pile up on target 12 and spill over the edges as slightly cooled masses which, as they start to fall, will be additionally sprayed and cooled by the spray heads 21 to be somewhat more solidified. These partially solidified masses then continue to fall, pass through grids 22, and then on to the first baffle 31 and from first baffle 31 to second baffle 31, and finally, to discharge from the lower baffle onto conveyor chain 27.

The result of the operation, as above, is to form the hot molten slag into individual masses or aggregates which have been somewhat cooled and have been slowed down in their fall so as to provide a time interval for expansion, and the slag masses which collect on conveyor chain 27 will be quite hot slag masses which have been expanded, it is believed, by gasses which are dissolved in the hot slag but which are forced out of the slag as it cools due to the fact that the slag as it cools becomes supersaturated, and such gases cause the formation of voids in the slag masses and thus puff the slag masses to provide a structure which will result in the desired light weight aggregate. It is also possible that some of the water with which the slag masses are sprayed, or steam formed therefrom, finds its way into the slag masses, and that the steam also has some effect in puffing the slag masses or providing voids therein. It is immaterial as to just how or why the voids are formed in the slag masses, since the desired puffing is a function of the treatment to which the slag has been subjected, as above described, and so far as the result is concerned, it is immaterial whether the puffing or expansion of slag is caused by dissolving gases or by steam or gases from some extraneous source.

The hot puffed slag which cools on chain conveyor 27, due to the slow speed of such conveyor, is subjected to annealing, at least to some degree. That is, due to the fact that the material cools en masse on the conveyor and the mass is a hot mass, cooling thereof will be at a relatively low rate, and thus there will be some annealing. When the expanded slag has been removed from the chamber it may be suitably crushed to provide aggregate of desired size, which crushing may be by passing the material through a cylinder crusher, through a swing hammer crusher, or any other suitable means for reducing the masses to aggregate size. After the expanded slag has been reduced more or less to aggregate size, it is then screened over suitable screens so as to obtain the desired gradation required for the particular use to which the expanded slag aggregate is to be

put. The reduction of the expanded slag to aggregate, and the specific use thereof, not being pertinent to the invention hereof, such will not be further described or discussed, particularly so since those skilled in the art will well understand the procedures required.

The inventions hereof having been described in detail, both as to the apparatus and the procedure of its use, I claim:

- 10 1. Apparatus for the manufacture of expanded slag and comprising: a stack structure, a stationary target mounted substantially centrally of the stack and adjacent the top thereof, pressure jets positioned above the target directed downwardly toward the upper portion of the target and generally tangentially thereof, spray heads mounted at substantially the level of the target and directed toward the target, generally tangentially thereof, means positioned below the target, in the path of slag masses discharging from the target, and interrupting free fall of such slag masses, the said means comprising a substantially horizontal grid supported in the stack and below the grid, one positioned below another, plate members extending oppositely from the wall of the stack toward and overlapping adjacent the center of the stack.
- 15 2. Apparatus for the manufacture of expanded slag and comprising: a stack structure, a highly refractory stationary target against which a poured stream of molten slag may impinge mounted substantially centrally of the stack adjacent the top thereof, fluid projecting nozzles mounted about the target, directed toward the target and discharging substantially tangentially thereto, a grid and downwardly inclined means positioned below the target in the path of slag masses discharged from the target, whereby the fall of slag masses discharging from the target will be retarded.
- 20 3. The apparatus of claim 2 wherein the downwardly inclined means intercepting slag masses discharging from the target comprise substantially plane surfaces mounted one below another, spaced apart vertically, oppositely inclined downwardly from the periphery of the stack toward its center and overlapping, whereby slag masses falling upon the upper of such means will be directed downwardly and discharged to the next succeeding downwardly inclined means.
- 25 4. The apparatus of claim 3 wherein the downwardly inclined means are provided with multiple drainage openings extending therethrough, whereby water accompanying the slag masses may drain away.
- 30 5. The apparatus of claim 4 wherein adjacent the bottom of the stack and below the lowermost downwardly inclined slag intercepting means, there is provided means receiving the slag masses and discharging them exteriorly of the stack.

DEE G. WHEELER.
